UNITED STATES PATENT OFFICE

ARCHIBALD McCALLUM, OF HALIFAX, ENGLAND, ASSIGNOR TO W. AND I. SLOANE, OF NEW YORK, N. Y.

DESIGN FOR A CARPET-PATTERN.

Specification forming part of Design No. 6,004, dated July 23, 1872.

Specification describing a new and original Design for a Carpet, invented by ARCHIBALD McCALLUM, of Halifax, in the county of York, England.

The accompanying photographic illustration fully represents my new design.

The invention relates to a new carpet-design, in which an elliptic figure in a light straight-lined border and a rectangular figure in an irregular border constitute the main features both figures being ornamented as shown.

I claim as my invention—

The design for a carpet, as shown.

ARCHIBALD McCALLUM.
